UNITED STATES PATENT OFFICE

2,620,488

SOFA CHAIR AND BED COMBINATION

Edward E. Woller, Kenosha, Wis., assignor to
 Simmons Company, New York, N. Y., a corporation of Delaware

Application July 29, 1947, Serial No. 764,285

4 Claims. (Cl. 5—21)

1

The main objects of this invention are, to provide an improved type of collapsible or fold-away bed unit; to provide a bed unit of this kind particularly adapted for use in association with sofa-type furniture for converting it from its normal sofa use to a bed; to provide an improved trundle-type bed unit of this kind adapted for convenient stowage under the sofa furniture wherewith it is associatable for bed conversion purposes; to provide a bed unit of this kind with an improved foldable sectional bed bottom whereby the unfolding of said bed-bottom sections into coplanar relationship automatically elevates and disposes said sections at the proper height to cooperate with the sofa furniture to form a full-sized bed; to provide an improved sectional bed-bottom unit of this kind which may be used for a bed completely disassociated from the sofa furniture under which the bed unit is normally stowed; to provide improved latching means for anchoring said bed unit at the side of the sofa furniture when it is to be associated therewith to form a bed; to provide improved means actuated by said bed-bottom sections for automatically controlling the action of said latching means; and to provide an improved form of foldable trundle bed section embodying these several features particularly suitable for use with a two-unit separable sofa and chair ensemble.

In the accompanying drawings,

Fig. 1 is a perspective view of a two-unit separable sofa and chair ensemble wherewith an improved trundle bed unit embodying this invention is adapted for use in converting said ensemble into a full-sized bed. In this view the sofa and chair are shown in their separated positions with the trundle bed stowed under the sofa unit;

Fig. 2 is a front elevation of the sofa-chair ensemble with the trundle bed removed and supporting the sofa and chair unit cushions in position to convert the sofa-chair ensemble and trundle bed unit into a full-sized bed;

Fig. 3 is an end elevation of the assembly as shown in Fig. 2;

Fig. 4 is a side elevation of the trundle bed unit with the bed-bottom sections in their elevated coplanar relationship preparatory to having the sofa-chair cushions placed thereon;

Fig. 5 is a side elevation of the trundle bed unit with the bed-bottom sections in their collapsed or folded superimposed positions for stowage under the sofa unit;

Fig. 6 is an enlarged fragmentary plan view of the trundle bed unit with the bed-bottom sections in their extended coplanar positions; and

2

Fig. 7 is an enlarged fragmentary transverse sectional view showing the locking means whereby the trundle bed unit is anchored at the side of the sofa unit.

- 5 A convertible sofa-seat trundle-bed combination embodying this invention comprises a sofa unit 8, a chair or seat unit 9, and a trundle bed unit 10. The sofa and chair units, with the trundle bed unit stowed under the former, may be used in separated relationship or in associated relationship as a lounge or davenport, from which latter relationship they may be converted into a full-sized bed when the trundle bed unit is withdrawn and unfolded.
- 10 Except for their dimensions the sofa unit 8 and the chair unit 9 are of practically the same construction. Each embodies, respectively, a base frame 11 or 11', an end 12 or 12', and a back 13 or 13', supported on pairs of legs 14 or 14' and 15 or 15' wherein is mounted a mattress section 16 or 16' in turn supporting seat cushions 17 or 17' and back cushions 18 or 18'.
- 15 The frames 11 and 11' for these two units are of more or less the same construction. As shown in Fig. 7, such framework preferably is made of angle iron members so as to support the mattress section 16 or 16' a sufficient distance from the floor to provide stowage space for the trundle bed unit 10 under the sofa unit 8.
- 20 The mattress sections 16 and 16' may be of any suitable upholstered spring construction. The seat cushions 17 and 17' likewise may be of any suitable construction, preferably spring, and of a thickness so that, as will appear more fully hereinafter, when the trundle bed unit 10 is withdrawn and the bed-bottom sections are unfolded into their elevated coplanar positions and the cushions 17 and 17' are laid thereon (as shown in Fig. 2) the upper surface of the cushions 17 and 17' will be in the plane of the upper surface of the mattress section 16 and 16', thus forming a full, double-size, spring mattress bed.
- 25

30 Face boards 19 and 19' are arranged along the front of the frames 11 and 11', below the mattress section 16 and 16', so as to provide a finished appearance to these pieces of furniture. As will appear clearly from Fig. 3, the facing 19 is secured to the trundle bed unit 10 and, of course, moves with the unit when it is withdrawn from its stowed position.

35 The trundle bed unit 10 comprises a frame 20 whereon is mounted a main bed-bottom section 21 and an auxiliary bed-bottom section 22 hingedly connected together at 23 whereby, 40 through the medium of position-adjusting mech-

anism 24, the bed-bottom sections 21 and 22 may be collapsed or folded onto the frame 20 for stowage of the trundle-bed unit 10 under the sofa unit 8, or may be elevated in coplanar position at the side of the sofa unit and to which it may be anchored by automatically-actuated latch means 25.

The frame 20 is of more or less conventional construction. Preferably it is formed of angle bars and of an over-all length approximately equal to the over-all longitudinal dimension of the mattress section 16 of the sofa unit 8. Casters 26 permit the frame and its supported parts to be rolled into and out of stowage position under the frame 11 of the sofa unit 8.

The bed-bottom units 21 and 22 are likewise of the conventional angle bar construction wherein is secured the usual fabric 21 (see Fig. 6). The bed-bottom section 21 in length is slightly less than the over-all length of the supporting frame 20, whereas the bed-bottom section 22 is approximately equal to the length of the mattress section 16' of the seat unit 9. These bed-bottom sections are hinged together at 23 by means of brackets 28 and 29. One arm of each bracket is secured to the opposed ends of the side members of the bed-bottom sections 21 and 22. The other arms of the brackets are offset so as to space apart the sections 21 and 22 at their hinged ends when the sections are folded as shown in Fig. 5. The brackets 29 each have an ear 30 integrally formed thereon whereto is connected one of the links of the position-adjusting mechanism 24 shortly to be described.

A pair of legs 31 are foldably secured near the outer end of the bed-bottom section 22 so that in their extended positions they support the free end of the bed-bottom section 22 in its coplanar position with the bed-bottom section 21, when the latter is elevated by the action of the position-adjusting mechanism 24.

The position-adjusting mechanism 24 comprises two pairs of links 32 and 33, one link of each of which pairs is connected to a synchronizing link 34 to constitute a parallel linkage on either side of the frame 20, and a pair of actuating links 35, which effect the elevating and lowering of the bed-bottom section 21 on the frame 20, when the auxiliary bed-bottom section 22 is swung between its superimposed position over the bed-bottom section 21 and its extended coplanar position therewith.

The pair of links 32, at their lower ends, are rigidly connected in alignment to an equalizer rod 36 which is journalled at its ends in holes in the sides of the frame 20. At their upper ends, the links 32 have pivot pins 37 slidably supported in slots 38 formed in the adjacent ends of the sides of the bed-bottom section 21. The pair of links 33, at their lower ends, are rigidly connected to an equalizer rod 39 which is similarly journalled in the sides of the frame 20 and, at their upper ends, have pivot pins 40 slidably supported in slots 41 formed in the sides of the bed-bottom section 21.

Rollers 42 and 43, mounted on the inner ends of the pivot pins 37 and 40, respectively engage the under face of the angle bars, which constitute the side members of the main bed-bottom section 21, and facilitate the movement of the pivot pins in the slots 38 and 41 during the elevating and lowering of the bed-bottom section 21 through the action of the position-adjusting mechanism 24.

The synchronizing link 34 connects one of the

links of the pair 32 with one of the links of the pair 33 so that these links are caused to move in unison under the influence of the actuating links 35.

The pair of bed-bottom-section actuating-links 35 are pivoted to the ears 30 on the respective brackets 29 and to the pivot pins 37 for the pairs of links 32. Thus, the swinging of the bed-bottom section 22 on hinge 23 causes the link 35 to pull or push the links 32 (and one of the links of the pair 33 through the medium of the synchronizing link 34). This results in the raising and lowering of the bed-bottom section 21 as the auxiliary bed-bottom 22 is swung between its folded position with respect to the main bed-bottom section 21 and their extended coplanar positions. From Fig. 4 it will be noted that when the bed-bottom sections are in their coplanar positions a line through the pivots of the links 35 is disposed below the hinge 23. Accordingly, any weight on the main bed-bottom section 21 cannot exert a force sufficient to cause an upward swinging of the auxiliary bed-bottom 22 on its hinge 23.

A stabilizer bar 44 is pivotally connected at 45 to the inner side rail of the bed-bottom section 21, adjacent the end which is hinged at 23 to the auxiliary section 22, and at 46 to the corresponding side bar of the frame 20 but at the opposite end thereof. This stabilizing bar serves to restrict the bed-bottom section 21 to vertical movement relative to the supporting frame 20 as it is actuated by the position-adjusting mechanism 24.

The automatically-actuated latch means 25 comprises an arm 47 and an operating lever 48 arranged on each of the two inner corners of the supporting frame 20 adjacent the side thereof which is directly opposed to the front of the sofa unit 8 when the trundle bed unit 10 is arranged for converting the sofa and seat units into a bed. These parts are so mounted, as will appear presently, that shoulders 49 on the arms 47 are engageable between shoulders 50 and 51 (see Fig. 7) on the supporting frame 11 of the sofa unit 8 whereby to anchor the trundle-bed unit 10 at the side of the sofa unit 8 when the bed-bottom section 21 is elevated to convert the sofa- and seat-units into a bed.

As most clearly shown in Fig. 7, each of the arms 47 is connected to the supporting frame 20 by means of a pair of pins 52 and 53 operating in a slot 54. The slot 54 is provided with an offset 55 which is adapted to receive the pin 53 when the pin 52 is at the forward end of the slot 54 so as to permit the arm 48 to automatically drop into a position to permit the engagement of the shoulder 49 between the shoulders 50 and 51.

Whenever the pin 53 is depressed from the offset 55 and the pin 52 is moved away from the end of the slot 54, the arm 47 will be retained in its horizontal position. Such will be the condition when the trundle-bed unit 10 is pushed fully under the sofa unit 8 and the shouldered ends of the arms 47 strike the back of the sofa unit frame 11. The shoulder 50 is formed as the result of cutting a notch 56 in the side flange of a vertical, end, angle bar which constitutes a part of the sofa frame 11. This notch is of a height slightly greater than the width of the arm 47 but is positioned in the flange of the angle bar slightly out of alignment with the arm 47 when in its horizontal position. This locates the upper end of the shoulder 50 in a position to normally engage the shoulder

49 and limit the withdrawing movement of the trundle-bed unit 10 from under the sofa unit 8. However, by slightly raising the bed-bottom unit 10 at its inner corners the arms 8 could be brought into registration with the respective notches 56 so that the shoulders 49 could pass outwardly through these notches and the trundle-bed unit 10 could be moved away from the sofa unit for use as a bed section independently of the sofa and seat units 8 and 9.

The shoulder 51 is formed by locating an angle bar 57 on the sofa unit frame 11 with the outer end of said angle bar opposed to but spaced slightly inward from the notched flange of the angle bar which forms the shoulder 50. This provides a space between the shoulders 50 and 51 into which the shoulder 49 drops when the arm 47 is allowed to occupy the tilted position shown in Fig. 7.

As will be shown most clearly in Fig. 6, the levers 48 are of angular form and pivoted at 58 so that the arms thereof parallel to the sides of the supporting frame 20 extended outwardly under the respective arms 47. The inner and angularly-disposed arms of the levers 48 extend inwardly away from the side bar of the supporting frame 20, to which the levers 48 are pivoted so that the ends of these angularly-disposed arms extend under the corresponding side bar of the bed-bottom section 21. Thus the angular position of the arms 47, with regard to the end bars of the supporting frame 20 to which they are pivoted, depends upon the position of the bed-bottom section 21 with respect to the supporting frame 20. When the bed-bottom section 21 is in its folded or collapsed position the inner side rail thereof contacts the inwardly-extending angularly-disposed arms of the levers 48 so as to elevate the outer ends of the arms 47 and dispose the shoulders 49 above and out of position for engagement with the shoulders 50 on the sofa frame 11. On the other hand, when the bed-bottom section 21 is elevated, as shown in Fig. 7, the arms 47 are normally actuated by gravity to bring the shoulders 49 into a lowered position between the shoulders 50 and 51.

The operation of these several units to convert them from a disassociated sofa and chair arrangement to a bed, and vice versa, is briefly as follows.

The chair unit 9 is placed at the end of the sofa unit 8 to form a couch or davenport. Thereupon the trundle-bed unit 10 is withdrawn from under the sofa unit 8 to a position immediately in front of the sofa unit 8. The trundle bed unit 10 reaches the limit of its forward or withdrawing movement when the shoulders 49 on the arms 47 strike against the shoulders 50. This pulls the arms 47 outward so as to bring the pins 52 to the ends of the slots 54 and locate the pins 53 in position to be received in the offsets 55 as the bed-bottom section 21 moves into its elevated position.

The auxiliary bed-bottom section 22 is thereupon swung on the hinge 23 and the legs 31 swung outwardly to rest upon the floor. Such swinging of the bed-bottom section 22 causes the links 35 to elevate the links 32, which movement is communicated to the links 33 by the synchronizing bar 44, whereupon the bed-bottom section 21 is elevated to the position shown in Fig. 4. The upward movement of the bed-bottom section 21 releases the levers 48 so that the shouldered ends of the arms 47 may

drop and position the shoulders 49 between the shoulders 50 and 51. Consequently, the trundle-bed unit 10 is anchored at the front of the sofa and chair units 8 and 9 against accidental displacement so long as the three units are associated for the formation of a bed.

The back cushions 18 and 18' are laid aside. The seat cushions 17 and 17' are placed on the bed-bottom sections 21 and 22, as shown in Fig. 2. The upper faces of the cushions 17 and 17' are disposed in the same plane as the upper face of the mattress sections 16 and 16' of the sofa and chair units 8 and 9 respectively. This makes a full-sized bed with practically no noticeable break in the upper surface thereof.

When the units are to be returned to normal sofa and chair use, the cushions 17 and 17' are replaced on the mattress sections of the sofa and chair units 8 and 9. The bed-bottom section 22 is then swung to a position over the bed-bottom section 21. This causes the position-adjusting mechanism 24 to lower the bed-bottom section 21. As the bed-bottom section 21 comes into its fully lowered position on the supporting frame 20 it engages the levers 48, which causes a retraction of the arms 47 so as to raise the shoulders 49 above the shoulders 51. Thereupon the trundle-bed unit may be returned to its stowed position under the sofa unit 8.

Variations and modifications in the details of structure and arrangement of the parts may be resorted to within the spirit and coverage of the appended claims.

I claim:

- 35 1. In a sofa bed of the class described, the combination with a sofa frame mounting an upholstered section in spaced relationship to the floor and having a plurality of cushions of predetermined thickness supported on said upholstered section for normal sofa use, of a trundle-bed unit movable between a position under the upholstered section of said sofa frame and a position alongside the front thereof, said trundle-bed unit comprising a castered supporting frame, a main bed-bottom section, links supporting said main bed-bottom section on said frame to permit movement of said bed-bottom section between a lowered position on said frame and a vertically-elevated position above said frame at a height such as will 50 dispose said sofa cushions when placed on said main bed-bottom section with the upper surface of said cushions in the plane of the upper surface of said upholstered section, an auxiliary bed-bottom section hinged to said main bed-bottom section and swingable between folded superimposed and extended coplanar positions with respect to said main bed-bottom section, a bed-bottom section actuating-link connecting said auxiliary bed-bottom section to one of said links 55 for said main bed-bottom section whereby the swinging of said auxiliary bed-bottom section automatically effects the elevating and lowering of said main bed-bottom section on said frame, legs for supporting the free end of said auxiliary bed-bottom section in coplanar disposition with said main bed-bottom section in its elevated position on said frame, an arm pivoted on said trundle-bed unit supporting frame, a shoulder on said arm engageable with shoulders on said sofa frame for anchoring said trundle bed unit in unshiftable position at the front of said sofa, and means engageable by one of said bed-bottom sections when said sections are in their superimposed folded positions for shifting said arm to retract the shoulder thereon from engagement with the

shoulders on said sofa frame to permit movement of said trundle-bed unit relative to said sofa.

2. In a sofa bed of the class described, the combination with a sofa frame mounting an upholstered section in spaced relationship to the floor and having a plurality of cushions of predetermined thickness supported on said upholstered section for normal sofa use, of a trundle-bed unit movable between a position under the upholstered section of said sofa frame and a position alongside the front thereof, said trundle-bed unit comprising a castered supporting frame, a main bed-bottom section, links supporting said main bed-bottom section on said frame to permit movement of said bed-bottom section between a lowered position on said frame and a vertically-elevated position above said frame at a height such as will dispose said sofa cushions when placed on said main bed-bottom section with the upper surface of said cushions in the plane of the upper surface of said upholstered section, an auxiliary bed-bottom section hinged to said main bed-bottom section and swingable between folded superimposed and extended coplanar positions with respect to said main bed-bottom section, a bed-bottom section actuating-link connecting said auxiliary bed-bottom section to one of said links for said main bed-bottom section whereby the swinging of said auxiliary bed-bottom section automatically effects the elevating and lowering of said main bed-bottom section on said frame, legs for supporting the free end of said auxiliary bed-bottom section in coplanar disposition with said main bed-bottom section in its elevated position on said frame, a pair of arms one of which is slidingly pivoted on each end of said trundle-bed frame with the ends extending beyond the adjacent intermediate side of said frame, a shoulder on the end of each of said arms each engageable with a shoulder on said sofa frame for anchoring said trundle-bed unit in unshiftable position at the front of said sofa, and a lever pivoted at each end of said adjacent intermediate trundle-bed frame side in position to have one arm each of said levers engaging the adjacent shouldered arm and to have the other lever arm disposed in a position to be engaged by said main bed-bottom section in its folded or collapsed position whereby the engagement or disengagement of said arm shoulders with said sofa-frame shoulders is dependent upon the unfolded or folded relationship of said bed-bottom sections.

3. In combination with a sofa, a trundle-bed unit movable between a position under said sofa and a position alongside of said sofa, said trundle-bed unit comprising a supporting frame, a main bed-bottom section, links supporting said main bed-bottom section on said frame to permit movement of said bed-bottom section between a lowered position on said frame and a vertically-elevated position above said frame, an auxiliary bed-bottom section hinged to said main bed-bottom section and swingable between folded superimposed and extended coplanar positions with respect to said main bed-bottom section, a bed-bottom section actuating-link connecting said auxiliary bed-bottom section to one of said links for said main bed-bottom section whereby the swinging of said auxiliary bed-bottom section automatically effects the elevating and lowering of said main bed-bottom section on said frame, legs for supporting the free end of said

auxiliary bed-bottom section in coplanar disposition with said main bed-bottom section in its elevated position on said frame, an arm pivoted on said trundle-bed unit supporting frame, a shoulder on said arm engageable with shoulders on said sofa for anchoring said trundle-bed unit in unshiftable position at the front of said sofa, and means engageable by one of said bed-bottom sections when said sections are in their superimposed folded positions for shifting said arm to retract the shoulder thereon from engagement with the shoulders on said sofa to permit movement of said trundle-bed unit relative to said sofa.

15 4. In combination, a sofa and a chair each having an arm rest at only one end thereof whereby said sofa and chair are adapted to be abutted at their other ends to form an integral unit, said sofa and chair each having an upholstered section disposed at the same predetermined height above the floor and having a cushion of the same predetermined thickness normally supported on said upholstered section to form a seat, a trundle-bed unit movable from a stowed position under the upholstered section of said sofa to a forwardly disposed position in juxtaposition with the front of said sofa, said trundle-bed unit comprising a movable supporting frame, a main bed-bottom section substantially co-extensive with the width of said sofa, links supporting said main bed-bottom section on said frame for movement from a lowered position to a predetermined elevated position, an auxiliary bed-bottom section of length substantially equal to the width of said chair hinged to one end of said main bed-bottom section and swingable from a superimposed position on said main bed-bottom section to an extended position co-planar with said main bed-bottom section and in juxtaposition with the front of said chair, an actuating link connecting said auxiliary bed-bottom section with one of said supporting links whereby the swinging of said auxiliary bed-bottom section to said co-planar extended position is effective to raise said main bed-bottom section to said elevated position, and foldable legs on said auxiliary bed-bottom section for supporting said auxiliary section in said extended position, said predetermined height and said predetermined thickness and said predetermined elevated position being such that when said cushions are disposed upon said bed-bottom sections the upper surfaces of said cushions are substantially co-planar with the upper surfaces of said upholstered sections to form therewith a unitary bed.
